UNITED STATES PATENT OFFICE.

THEODORE H. SLOAN, OF CHARLEROI, PENNSYLVANIA, ASSIGNOR TO MACBETH-EVANS GLASS COMPANY, OF PITTSBURGH, PENNSYLVANIA, A CORPORATION OF PENNSYLVANIA.

GLASSWORKING MACHINE.

Application filed March 24, 1921. Serial No. 455,026.

To all whom it may concern:

Be it known that I, THEODORE H. SLOAN, a citizen of the United States, and a resident of Charleroi, in the county of Washington, State of Pennsylvania, have invented a new and useful Improvement in Glassworking Machines, of which the following is a specification.

The invention relates to apparatus and machines for finishing glass articles in a heated condition, and is particularly applicable to machines for crimping the upper ends of lamp chimneys after they have passed through a heating furnace.

15 The object of the invention is to provide a glass-finishing apparatus in which the finishing tool is moved to and from its operative position in dependable coordination with the movement of a conveyor for carrying 20 articles through a heating furnace so that the tool will be brought into proper registry with each article carried by the conveyor.

A further object is to provide a glass-finishing machine having an article positioner 25 which engages and positions the article with relation to the finishing tool before the article is engaged by the tool; and which holds the article until after the tool has been disengaged from it.

A still further object is to provide a glass-finishing machine, the operating parts of which may be adjusted to finish glass articles of various sizes.

35 The invention is illustrated in the accompanying sheets of drawings in its applicability to apparatus for crimping the upper end of lamp chimneys. Fig. 1 is a somewhat diagrammatic plan view of the end of a heating furnace and a portion of a conveyor for carrying chimneys through the furnace, a crimping machine being indicated adjacent to the end of the furnace; Fig. 2 is a side elevation to enlarged scale of the crimping 40 machine, the plane of view being indicated by the line II—II, Fig. 1; Fig. 3 a right end view of the machine as seen in Fig. 2; Fig. 4 a horizontal sectional view taken on the line IV—IV, Fig. 2; Fig. 5 a vertical central sectional view to enlarged scale of the 45 crimping tool and article-positioner, the plane of view being indicated by the line V—V, Fig. 4; and Fig. 6 a fragmentary perspective view of the moving parts and 50 driving connections of the machine.

In the practice of the invention, glass articles such as lamp chimneys, are carried through a suitable heating furnace 1 by means of a conveyor which is preferably of the continuous type comprising a pair of 60 sprocket chains 2 having supporting plates 3 extending between and attached to them at definite positions with relation to the links of the chains. The plates are provided with or shaped to form cups or saddles 4 for 65 loosely supporting the glass articles. When the apparatus is used for crimping the tops of lamp chimneys, the saddles 4 are provided with central openings so that the lower ends of the chimneys are exposed to 70 the heat below the conveyor, and the furnace is constructed to heat both ends of the chimneys. The heating of the lower ends is for the purpose of fire finishing their rough and sharp edges, and the heating of the upper 75 ends is to so soften the glass that it may be readily shaped by the crimper located at the end of the furnace.

The glass-finishing machine in its preferred form comprises a frame provided 80 with a carrier which is movable to and fro parallel to the conveyor and in line of its advance. Borne by the carrier, there is a finishing tool mounted for reciprocatory movement toward and from the conveyor. 85 Separate connections are provided between the conveyor and the carrier and tool for co-ordinately effecting their movements in both directions and at the proper times with relation to the advance of the conveyor. These 90 connections, as well as the support for the carrier, are provided with suitable adjustments so that the carrier may be positioned, and the tool properly operated, at any desired distance from the conveyor, the distance depending upon the size of the articles being finished. The machine also includes an article-positioner which successively engages and brings the articles, carried loosely in the saddles of the conveyor, to the proper 95 position with relation to the tool before the tool is moved into engagement with the article, and which also holds each engaged article upon the conveyor until after the tool has been disengaged from the article. 100

Having reference now to the chimney crimper which is the embodiment of the invention illustrated in the drawings, all the parts of the crimping machine are mounted upon a frame 5 arranged at the side of the 110

conveyor. On the upper portion of the frame a support for the crimper carrier is mounted for vertical adjustment. This support comprises a horizontal bar 6 attached 5 to a block 7 which is connected to a small housing 8 by means of bolts 9 extending through a slot 10 formed in the frame. The face of the frame is provided with a rack 11 with which there meshes a pinion 12 mounted 10 on a small shaft 13, which shaft is rotatably mounted in the housing 8 and is provided at its outer end with an operating handle 14. By loosening the bolts 9, the handle 14 may be turned to move the carrier support upwardly or downwardly to the required position, and when in such position the bolts 15 may be again tightened.

The crimper carrier, indicated at 15, is 20 slidably mounted upon bar 6, and is provided on its side with a socket 16 engaged by the outer end of an oscillating arm 17 secured to a vertical shaft 18. This shaft is rotatably mounted at its opposite ends in brackets 19 and 20 forming parts of the 25 machine frame, and is provided with a collar 21 bearing upon the upper edge of bracket 20 to hold the shaft in its vertical position. To the lower end of shaft 18, there is attached an arm 22 provided with a projection 30 in the form of a roller 23 extending into a cam slot 24 so formed in the periphery of a drum 25 that as the drum rotates the arm will be oscillated. For rotating the drum 25 in positive and certain coordination 35 with the advance of the conveyor, the drum is mounted upon a shaft 26 provided with a sprocket wheel 27 which is engaged and rotated by the sprocket chain of the conveyor. By attaching the conveyor supports 3 with their saddles 4 at regular intervals to the links of the sprocket chain, the cam drum 25 may be so rotated that the crimper carrier properly advances in registry with each support. The cam slot 24 40 and the lengths of the oscillating arms 17 and 22 are so proportioned that the forward movement of the crimper carrier is at the same rate of speed as that of the advancing conveyor, and so that there is a quick return 45 of the carrier. For adjusting the driving connections of the crimper carrier, the arm 17 is slidably mounted on a squared section of shaft 18, and is clamped thereto by means 50 of a yoke 28.

55 The crimping tool 29, which may be of familiar or any desired construction, is attached to the lower end of a rod 30 mounted for vertical reciprocation in the outer end of carrier 15. Rod 30 is preferably reciprocated by connections extending from a cam 31 mounted on shaft 26 adjacent to drum 25. The driving connections include a bell crank lever, pivoted at 32, to the machine frame, and having an arm 33 bearing upon cam 31 60 and an arm 34 adjustably attached to a rod

25 by means of a set screw 36 having an operating handle 37. For holding the arm 33 upon or toward the face of cam 31, the bell crank lever is provided with a projection 38 to which there is attached a spring 39 adjustably anchored to the machine frame by means of a pin 40. To shaft 35 there is attached, by means of a universal joint 41, the lower end of a shaft 42, the upper end of which is attached by a similar joint to one 70 end of a rocking arm 43. The other end of arm 43 is attached to rod 30 by means of a link 45, universal pivot joints 46 and 47 being used to make the connections. Rocking arm 43 is pivoted at 48 to the upper end of 80 a bracket 49 supported by the vertically adjustable block 7 of the carrier support, so that but a single operation is necessary for adjusting positions of the crimper carrier and the rocking arm. This train of driving connections preferably includes a yielding section 44 to prevent the machine from 85 injury in case all adjustments are not properly made.

The connections for vertically reciprocating the crimper are such that the downward movement is effected by the spring 39 and its upward movement by the projections upon the cam 31. Thus the crimper bears 90 yielding upon the chimneys, which accordingly may vary in length without liability of being crushed by the crimper.

The chimney positioner is preferably borne by the tool carrier and is so constructed that it is normally urged toward chimney-engaging position and is moved from such position by the upward movement of the crimper after the crimper has moved from a chimney. The positioner preferably 100 comprises a pair of arms 50 pivotally suspended as at 51 from the upper portion of the crimper carrier, each arm being provided at its lower end with a pair of fingers 52. Each finger is clamped to the arm 50 by means of a screw 53 and may be independently adjusted toward and from the center line of the crimper. That the two positioning arms 105 may swing simultaneously to and from chimney-engaging position, they are provided with laterally extending fingers 54, the outer ends of which are provided with teeth 55 forming segmental pinions which mesh with each other in the line of reciprocation of the crimper. These fingers extend 110 into a slot 66 formed in the crimper-supporting rod 30.

By suspending the arms 50 in the manner shown, they are normally urged by gravity toward chimney-engaging position, preferably, however, springs 51^a (Fig. 4) are provided to urge the arms inwardly. To move the arms outwardly upon the upward movement of the crimper, each may be provided with a plate 56 having a beveled edge lying 115 in the path of movement of the upper por- 120

tion of the crimper. The arrangement is such that the crimper rises from a chimney before it strikes the plates 56, and hence the positioning arms remain in chimney-engaging position until after the crimper has been disengaged from a chimney.

The machine includes means for lubricating the bearing parts of the tool carrier and the crimper rod 30, and also for feeding oil to the crimping tool. For this purpose an oil cup 57 is mounted upon a bracket 58 carried by the vertically adjustable bracket 49. A tube 59 leads downwardly from the cup to a trough 60 attached to the crimper carrier so that oil may flow upon bar 6 to afford lubrication for the crimper carrier, and upon rod 30 to lubricate its bearing within the tool carrier. Sufficient lubricating oil is caused to flow that some of it runs down the rod 30 upon the top of the crimper, which is provided with vertical ducts 61 through which the oil flows upon the crimping surface.

The operation of the machine will now be explained. Before setting the machine in operation, it is adjusted to the size of chimneys which it is desired to crimp. The crimper-carrier support adjustment is effected by loosening the bolts 9 and turning the small shaft 8 until the support 6, 7 is in its desired position, after which the bolts are tightened. This adjustment also positions the rocking arm 43 which is pivoted to bracket 49 supported by block 7 of the carrier support. Arm 17 is then vertically adjusted upon shaft 18 so that its end is engaged by socket 16 of the crimper carrier. The connection of shaft 35 to bell crank lever arm 34 may then be adjusted in proportion to the two previously mentioned adjustments so that the crimper will be in its proper position with relation to the chimneys.

The apparatus being thus adjusted, chimneys are placed loosely upon the saddles 4 of the conveyor as they enter the furnace, and the conveyor is caused to travel at such speed as may be necessary to have the chimneys properly heated as they emerge from the furnace. The crimper carrier is reciprocated parallel to and in the line of movement of the conveyor, the driving connections being from one of the sprocket chains of the conveyor through sprocket wheel 27, cam drum 25, arm 22, shaft 18 and arm 17 which engages the crimper carrier. Simultaneously with the forward and backward reciprocation of the crimper carrier, the crimper is vertically reciprocated, the driving connections being through shaft 21, cam 31, bell crank lever 33, 34, rods 35 and 42, rocking arm 43, link 46 and rod 30. The universal joints 46 and 47 at the ends of link 45 permit of the crimper rod 30 to be horizontally reciprocated by the crimper carrier while the

rod is being moved vertically. When a chimney moves to its position beneath the crimper, the chimney-engaging arms 50 are held outwardly by the crimper which is then in its upward position. As the crimper moves downwardly the arms 50 gradually swing toward the chimney and engage it before the crimper reaches its top. Thus, the positioning arms bring the chimney to, and hold it in, the position required for the proper functioning of the crimper. Near the end of the forward movement of the carrier, the crimper is caused to rise from the chimney and becomes disengaged therefrom before the crimper strikes the plates 56 of the chimney-engaging arms 50 and moves the arms from chimney-engaging position. By reason of this operation, the chimney may not be moved from its support in case the crimper should happen to stick to the top of it.

The crimping machine has been found to be very effective in operation. The chimneys are properly crimped regardless of the small variations usually incident to the conditions of operations, such variations being in the thickness of the glass, in the lengths of the chimneys, and in the degrees of plasticity to which the glass is brought by reason of different thicknesses of glass. The chimneys may rest loosely upon their saddles thus making it unnecessary to provide special clamps for engaging them. This manner of supporting the chimneys is made possible largely by reason of the direct and positive coordination of the moving parts with the advance of the conveyor and by the operation of the positioning mechanism.

According to the provisions of the patent statutes, I have described the principle and operation of my invention together with what I now consider to be the best embodiment thereof. However, I desire to have it understood that, within the scope of the appended claims, the invention may be practiced by other forms of construction, and by machines embodying other details of construction, than that specifically shown and described herein.

I claim:

1. In a glass-finishing apparatus, the combination of a sprocket chain conveyor for carrying glass articles through a heating furnace, a finishing tool, a sprocket wheel engaged and rotated by the sprocket chain, and separate connections between said wheel and tool for moving the tool parallel with the conveyor and for reciprocating the tool toward and from the conveyor.

2. In a glass-finishing apparatus, the combination of a sprocket chain conveyor for carrying glass articles through a heating furnace, a finishing tool, a sprocket wheel engaged and rotated by the sprocket chain, and separate connections between said wheel

and tool for positively moving the tool forwardly and backwardly parallel with the conveyor and toward and from the conveyor.

3. In a glass-finishing apparatus, the combination of a conveyor for carrying glass articles through a heating furnace, a frame, a tool carrier mounted on the frame for reciprocating movements parallel to the conveyor, a pivoted oscillating arm for moving said carrier, and connections coordinated with the movement of said conveyor for oscillating said arm.

4. In a glass-finishing apparatus, the combination of a conveyor for carrying glass articles through a heating furnace, a frame, a tool carrier slidably mounted on the frame for reciprocating movements parallel to the conveyor, a finishing tool mounted for reciprocating movement in said carrier, a pivoted oscillating arm for moving said carrier, a pivoted oscillating arm for reciprocating the tool with relation to the carrier, and connections coordinated with the movement of said conveyor for oscillating said arms.

5. In a glass-finishing machine, the combination of a support for glass articles, a tool carrier adjacent to said support, a finishing-tool mounted in the carrier for movement to and from the support, and an article positioner movable to and from an article and having its movements controlled by those of said tool.

6. In a glass-finishing machine, the combination of a support for glass articles, a tool carrier adjacent to said support, a finishing tool mounted in the carrier for movement to and from the support, and a movable article positioner normally urged toward article-engaging position and movable from said position by the movement of said tool from the support.

7. In a glass-finishing machine, the combination of a support for glass articles, a tool carrier adjacent to said support, a finishing tool mounted in the carrier for movement to and from the support, a pair of oppositely disposed arms pivotally suspended from said carrier and normally urged toward article-engaging position, and means whereby said arms are moved from article-engaging position by the movement of said tool from the support.

8. In a chimney-crimping machine, the combination of a support for glass chimneys, a tool carrier adjacent to said support, a crimper mounted in the carrier for movement to and from the support, a pair of chimney-engaging arms pivotally suspended from said carrier one on each side of the crimper and provided with intermeshing segmental gears, and projections on said arms engageable by the crimper on its movement from the support whereby the arms are moved from article-engaging position.

9. In a glass-finishing apparatus, the combination of a conveyor for carrying glass articles through a heating furnace, a frame, a tool carrier mounted on the frame for movements parallel to the conveyor, a finishing tool and an article positioner each borne independently by said carrier, connections coordinated with the movement of said conveyor for moving said carrier, and means for operating said tool and positioner.

10. In a glass-finishing apparatus, the combination of a conveyor for carrying glass articles through a heating furnace, a frame, a tool carrier mounted on the frame for reciprocating movements parallel to the conveyor, a finishing tool mounted for reciprocating movement on said carrier, an article positioner borne by the carrier and movable to and from an article in coordination with the reciprocation of the tool, and connections coordinated with the movement of said conveyor for reciprocating said carrier on the frame and said tool in the carrier.

11. In a glass-finishing machine, the combination of a support for glass articles, a tool carrier adjacent to said support, a finishing tool mounted in the carrier for movements to and from engagement with an article on the support, an article positioner borne by the carrier and movable from article-engaging position by the tool after the tool has moved from article-engaging position.

12. A glass-finishing apparatus, comprising a conveyor for carrying glass articles through a heating furnace, a finishing tool carrier, a cam rotatable by the conveyor, and a rotatable shaft provided with an arm engaging said cam and with a second arm engaging said carrier whereby the carrier is moved forwardly and backwardly parallel to the conveyor.

13. A glass-finishing apparatus, comprising a conveyor for carrying glass articles through a heating furnace, a finishing-tool carrier, a cam rotatable by the conveyor, a rotatable shaft provided with an arm engaging said cam, and a second arm mounted for longitudinal adjustment upon said shaft and engaging said carrier whereby the carrier is moved forwardly and backwardly parallel to the conveyor at variable positions from the conveyor.

14. A glass-finishing apparatus, comprising a conveyor for carrying glass articles through a heating furnace, a frame, a finishing tool carrier mounted on said frame for adjustment toward and from said conveyor, a cam rotatable by the conveyor, a rotatable shaft provided with an arm engaging said cam, and a second arm mounted for longitudinal adjustment upon said shaft and engaging said carrier whereby the carrier is moved forwardly and backwardly parallel to the conveyor.

15. A glass-finishing apparatus comprising a conveyor for carrying glass articles through a heating furnace, a frame provided with a movable carrier, a finishing tool mounted in the carrier for movements toward and from the conveyor, a cam rotatable by the conveyor, and connections between said cam and tool for moving the tool toward and from the conveyor, said 10 connections including a bell crank lever having one arm engaging said cam, a rod connected to the other arm of said lever, and a rock shaft having one arm connected to the other end of said rod and having its 15 other arm attached to said tool.
16. A glass-finishing apparatus comprising a conveyor for carrying glass articles through a heating furnace, a reciprocable carrier provided with a finishing tool moveable in the carrier toward and from said conveyor, said carrier being adjustable toward and from the conveyor, a cam rotatable by said conveyor and adjustable connec-

tions between said cam and tool for moving the tool toward and from the conveyor in 25 variable adjustable positions of the tool carrier.

17. A glass-finishing apparatus, comprising a conveyor for carrying glass articles through a heating furnace, a finishing-tool 30 carrier mounted for reciprocatory movement parallel to the conveyor, a finishing tool mounted in said carrier for reciprocatory movement at right angles to the conveyor, cams rotatable by the conveyor, and 35 adjustable connections between said cams and the carrier and tool for reciprocating them in variable adjustable positions of the carrier with relation to the conveyor.

In testimony whereof, I have hereunto set my hand.

THEODORE H. SLOAN.
